UNITED STATES PATENT OFFICE

2,507,707

LAMP RADIO

Harry A. Greener, Trucksville, Pa., assignor to
 Pennsylvania Electronics Incorporated, Philadelphia, Pa., a corporation of Pennsylvania

Application December 22, 1945, Serial No. 636,701

12 Claims. (Cl. 250—14)

1

This invention relates to an article of furniture and in particular to a table model lamp with a complete radio receiver including a chassis incorporated in the pedestal and an antenna therefor in the lamp shade.

One of the objections to building radio receiving sets in lamps and the like is the awkward appearance resulting from the combination; therefore, the primary object of this invention is to make the combination in such a manner that the general and outward appearance of the lamp is not altered and which from all outward appearances will have the same appearance as a corresponding lamp without a radio set therein, the radio set elements being completely concealed. It is contemplated to supply these lamps in pairs, particularly for use in boudoirs, or on pianos, mantelpieces, and the like, with the radio set incorporated in only one of the lamps.

In incorporating radios in articles of furniture, and even in automobiles and other devices, the radio receiver chassis is substantially inaccessible; therefore, this invention involves a lamp having a pedestal with a removable cover in which the light bulbs of the lamp, antenna, and the complete radio receiver chassis, are mounted upon the said cover and removable therewith.

A further objection to combining radio receiving sets, particularly in lamps, is that it has been found advantageous to mount the antenna loop in a vertical position and turn the carrier or signal to such a position that the antenna will cover the angular incidence of incoming radio waves and this necessitates turning the lamp, sometimes to awkward positions; whereas the antenna loop in the lamp of this combination is rotatably mounted within the shade so that it may be rotated independent of the shade to substantially any position without moving the shade or lamp.

The combination of a radio set with articles of furniture is also objectionable because space must be provided for the observance of the tuning dial and, therefore, this invention contemplates the use of a translucent plate, preferably with decorative designs thereon, forming a face of the lamp, and a projection system whereby the numerals on the tuning dial are projected on the plate so that they may readily be observed from the exterior of the lamp.

In combining a radio set with an article of furniture, it is also necessary to provide space for the knobs of the tuning condenser and volume control, and, as projecting knobs are objectionable, the knobs of the radio set of this invention

2

are incorporated in the cover of the pedestal and positioned in the upper surface thereof where they are concealed by the lamp shade.

In designing articles of furniture to include the complete elements of a radio set, it is also necessary to provide an open area covered by a screen to form a grille, and this usually results in an unsightly surface, so that in the pedestal of the lamp of this invention decorative grilles are provided at the four corners to provide a balanced cabinet, even though only the two grilles at the forward corners may be used.

Attempts to incorporate radio apparatus in table lamps with very little change or alteration in the design and construction of the lamp have been made but in doing so the units of the radio set have been separated and positioned at various points thereby complicating wiring, and particularly repairing; for this reason the pedestal of the lamp of this invention is formed with the complete radio receiver chassis incorporated therein and readily removable therefrom, as a unit.

Radio cabinets are commonly formed with the baffle surrounding the speaker stationary in the cabinet and when the radio receiver chassis is removed for repair and replaced, it is necessary to reposition the chassis so that the periphery of the speaker will register with the baffle, which is a relatively difficult operation. To overcome this, the baffle around the speaker of this invention is mounted on the chassis so that it is removable therewith and is, therefore, always registering with the speaker.

The purpose of this invention is to provide a lamp radio receiving set having a complete, compact chassis incorporated in the pedestal of a lamp and with the antenna rotatable in the shade thereof without detracting from the general appearance and design of the lamp.

In addition to the location and position of the antenna loop, the invention involves a new and novel loop design in which the fine wires of the loop are wound on a transparent plastic, which eliminates the possibility of shadow being cast upon the lamp shade or downward, as herein-after more fully described. The loop being formed of a frame of transparent plastic within the confines of the lamp shade and capable of being rotated substantially through a complete circle overcomes the disadvantages of the stationary antenna and at the same time makes it possible to use a cluster of light bulbs, thereby meeting requirements of the average user.

With the loop mounted in this manner, the con-

nections thereto or the lead-in wires from the chassis are concealed and by attaching the loop frame to a collar on the lamp stem the position thereof may readily be changed.

This novel loop design is a distinct improvement over all present forms of antenna loops, particularly as used in table model radios, as the loop is separate and distinct from the cabinet, stand or the like and does not come in close proximity to the wood or plastic of the cabinet or stand and is also separated from the steel chassis, all of which effect the efficiency of the loop because of their poor dielectric properties, and, in addition, they reduce the electrical Q of the loop.

Another distinctive feature is that this novel loop design is part of the light stem assembly which is in turn part of the main radio set chassis assembly. This makes the loop, light stem and the radio chassis one complete unit built around a vertical axis and capable of being removed from the radio cabinet with ease in one unit and with one convenient operation.

The cabinet of this radio receiver, which is incorporated in the pedestal of the lamp, is also unique in that the cabinet per se forms a complete unit, being open only at the top, and the entire radio set is installed from the top with one simple operation.

The grilles are removably mounted in the corners of the cabinet and are placed so that they provide unusual acoustical properties and permit full sound emission and also ventilation.

The object of this invention is, therefore, to provide a unique table lamp that may be formed with or without a radio set incorporated therein and in which the pedestal thereof is hollow and adapted to receive a complete radio receiver chassis. When used as a receiving set, the lamp is mounted above a cover of the pedestal with a radio chassis suspended from the under side thereof, and a lamp shade, light-bulbs and an antenna are mounted on a stem extending upward from the said cover, with the receiver, antenna, and light wires extending downward through the center of the stem and pedestal and outward through an opening at the base of the pedestal.

The invention also involves as a further object an arrangement of the receiver elements on a chassis in which the converter tube, the antenna and oscillator coils, the L. F. tube and the first L. F. transformer are grouped directly below the cover and above the tuning condenser; with the second L. F. transformer and second detector tube directly below and associated with the said tuning condenser; and with the loud speaker and baffle therefor, and power output and rectifier tubes grouped at the lower end thereof, thereby positioning the elements in their most logical groupings and providing a complete, compact chassis unit.

The invention also contemplates as a further object a loud speaker positioned perpendicular to a surface upon which the radio receiver is placed and in close proximity to said surface, thereby limiting the acoustic angle into which the loud speaker diaphragm radiates and, therefore, improving the low frequency air loading, which in turn increases the low frequency generally lacking in all small receivers.

The invention also embodies a particular arrangement of elements in a radio receiver chassis in which the elements, such as the rectifier tube and loud speaker, are closely associated so that the wiring connecting the parts is in its most simple form.

For a full and more complete understanding of the invention, reference may be had to the following description and accompanying drawings, wherein:

5 Figure 1 is a front elevation of the lamp radio with part of the shade broken away showing the antenna.

10 Figure 2 is a front elevation with parts broken away showing the radio receiver and lamp parts mounted on the cover of the pedestal and partly removed from the pedestal.

15 Figure 3 is a cross section through the pedestal with the radio set parts removed.

20 Figure 4 is a detail showing the radio receiver chassis mounted on the cover of the pedestal.

25 Figure 5 is a view showing the frame upon which the chassis parts are mounted.

30 Figure 6 illustrates the operating mechanism of the tuning condenser and also the means whereby the dial numerals are projected on the face of the pedestal.

35 Figure 7 shows a side elevation of the antenna mounting.

40 Referring now to the drawings wherein like reference characters denote corresponding parts, the device may be considered as divided into three parts, namely, the cover 10 upon which the chassis, antenna and lamp parts are mounted, a cabinet 11 and a lamp shade 12.

45 The cover 10 rests upon and may be attached to the upper end of a pedestal or cabinet 11, and the radio receiver chassis is suspended from the lower side of the cover, being mounted on a frame 13 with the antenna frame 14 mounted on the upper side and supported through a rotatable sleeve 15.

50 The antenna frame 14 is, in the design shown, formed of a flat strip of transparent plastic which substantially eliminates all shadow or other obstruction in the path of light rays from the light bulbs 16 and 17 around which the frame travels. The ends of the frame are secured to the upper end of the sleeve 15 by screws 18, and the lower end of the sleeve is provided with a groove 19 into

55 which a pin 20 projects, providing a stop at the ends of the groove and permitting rotation of the antenna through an angle of substantially 350°.

56 The antenna frame 14 is freely rotated by gripping the sleeve 15 with the thumb and forefinger and the position thereof may be adjusted to obtain the best sound effects, which are obtained when the plane of the antenna is perpendicular to the line of reception or a line extending to the sending station.

60 The fine antenna wires are positioned in grooves 21 and 22 in the frame 14 with their ends attached to eyelets 23 and 24, which are connected by wires 25 and 26 to an antenna coil 27 on the frame 13, the wires extending downward through the interior of the sleeve 15 and through an opening 28 in the cover 10.

65 The transparency of the material from which the frame 14 is made may be assumed to be complete except as to the places where the antenna wires are wound on the frame. The fineness of the wires and the spacing or spreading apart of these wires reduces the obstruction or any opaqueness which may be caused by the wires themselves. It will be noted that the spacing between the wires is relatively much greater than the space occupied by the wires. The principal or important feature is the fact that the light source, such as the lamp bulbs 16 and 17, gives

70 a diffused light instead of a point source of light.

The diffusion of the light around the small wires in turn is determined by such factors as the distance of the light source from the wires; also the intensity of the light source, as well as the distance of any panel or wall, as for example the lamp shade 12, which would receive a shadow; the latter being away from the wires gives more space for the diffused light to obviate any shadows.

The upper end of the loop or frame 14 is pivotally mounted in the upper part of the shade on the lamp stem 29 at the point 30 and by turning the sleeve 15 the antenna may be rotated around the stem independent of the shade and light bulbs. The sleeve 15 provides a cover and therefore protection for the leads of the antenna, and also supporting and controlling or adjusting means for the antenna.

The stem 29 extends downward through an opening 31 in the sleeve 15 and through an opening 32 in the cover 10 providing supporting means for the lamp, shade and antenna, and also providing a passage for wires 33 and 34, which supply current to the light bulbs above and to the radio receiver below, and extend downward through the pedestal and through a nipple 35 at the lower end. The stem 29 is locked in the cover by a lock nut 36 threaded on the lower end thereof as shown in Figure 2. The nipple 35 is mounted in an extending flange 37 of the chassis frame 13 by a lock nut 38 and when the lamp is assembled, this nipple 35 extends downward through an opening 39 in the base 40 of the pedestal 11 and is secured in place by a washer 41 and a lock nut 42. The washer 41 and nut 42 are positioned within a recess 43 when the lamp is assembled and the wires pass outward through a semi-circular recess 44 in the back of the base.

The lamp bulbs 16 and 17 are mounted on the stem 29 through a socket 45 with extensions 46, and the lamp shade 12 is held stationary at the upper end of the stem by the usual ornamental nut 47.

The lower end of the stem 29 also extends through an opening 48 in a flange 49 at the upper end of the chassis frame 13 and by this means the frame 13 is also held stationary in a recess in the lower surface of the cover 10. The flange 49 is also provided with openings 50 and 51 for the stems of the operating knobs.

The design and construction of the radio receiver chassis, which comprises the usual tubes, condensers, transformers and the like, all of which are standard articles of manufacture, is not described in detail. The relative positions of these parts, however, as illustrated in Figures 2 and 4, is described as with the antenna coil 27, the first I. F. transformer 52, converter tube 53, I. F. tube 54 and oscillator coil 55 positioned above the tuning condenser 56; and with the second I. F. transformer 57 and second detector tube 58 positioned below and directly associated with the tuning condenser, and the power output tube 59 and the rectifier tube 60 positioned at the lower end of the chassis, better results are obtained. The loud speaker 61 with its baffle 62 is also positioned adjacent the lower end of the chassis and is mounted so that the face thereof is perpendicular to the surface of a table or stand upon which the lamp may be placed so that the acoustic angle into which the loud speaker diaphragm radiates is reduced to 90° whereby the low frequency air loading is improved and this in turn increases the low frequency generally lacking in all small receivers.

The tuning condenser is provided with a drum 63 having calibrations 64 thereon and these are projected through a lens system 65 by a light source 66 to a translucent plate 67, forming the face of the cabinet as illustrated at 68 in Figure 1. The plate 67 may have designs as indicated by the numeral 69 thereon and similar plates may be used at the back and sides. It will also be understood that the numerals representing the calibrations of the tuning condenser may be projected to the face of the cabinet or to any point by any other means or in any manner.

The tuning condenser 56, in the design shown, is rotated by a knob 70 substantially hidden in a recess 71 in the cover 10 below the shade 12 and this knob is mounted on a shaft 72 extending downward through an opening 73 and provided with a pulley 74 at the lower end, which through a cable 75 rotates the tuning condenser, passing around a pulley 76 on the condenser and over idlers 77 and 78. The cable 75 may be provided with a spring 79 or other means for taking up slack therein. It will be understood that the knob of the tuning condenser may be located at any other point and may be connected to the condenser by any means. The device is also provided with a volume control knob 80 on a shaft 81 extending downward through an opening 82 and this turns a switch 83 and operates the usual volume control. This knob is also located in the recess 71 and substantially hidden by the cover 10 and lamp shade 12.

The pedestal 11 is formed with front and back walls 84 and 85 (see Figure 3), and end walls 86 and 87, and in the design shown the front and back walls are covered with removable plates 67 and 88, the plate 67 at the front covering an opening 89 through which the calibrations of the tuning condenser drum are projected, and these plates are slidably in grooves 90 at the edges. Similar plates 91 and 92 are also slidably held in grooves 93 at the ends.

The corners of the cabinet are shaped as shown in Figure 3 and the surfaces thereof are provided with openings 94, 95, 96 and 97, and these surfaces and openings are covered with grilles 98, 99, 100 and 101 respectively. These grilles are also slidably mounted in grooves 102 at the edges as shown.

The construction of the lamp radio receiving set will be understood from the foregoing description. In use the parts may be assembled as described and shown, particularly in Figure 1, and as stated before the lamps may be provided in pairs, one with and one without a radio set incorporated therein, and from general appearances it will be impossible to tell whether a lamp is provided with a radio or not. The lamp bulbs may be used independent of the radio set and either or both may be turned on or off as desired. In using the radio, it is only necessary to turn the knob 80 and then adjust the knob 70 until a station is tuned in, and these may be operated by the thumb and forefinger of a hand 65 that may be placed upward under the shade.

The antenna may readily be positioned for the best reception by turning it to substantially any angle without moving the lamp or shade.

The light bulbs may readily be changed or replaced without interfering with the operation of the radio set, and the tubes or other parts of the receiver may be changed or replaced by removing the entire chassis from the pedestal or cabinet and, as the chassis is permanently attached to the cover, it is only necessary to release

the chassis and cover by removing the nut 42 at the base and then the entire cover and chassis may be removed as a unit. With these parts removed from the pedestal all of the parts and the wiring of the radio are exposed and readily accessible.

While a preferred specific embodiment of the invention is hereinbefore set forth, it is to be clearly understood that the invention is not to be limited to the exact construction illustrated and described because various modifications of these details may be provided in putting the invention into practice within the purview of the appended claims.

What is claimed is:

1. A radio apparatus comprising, in combination, a table lamp having a hollow pedestal, a cover, and a shade, and a radio receiving set having a chassis positioned in the pedestal of the lamp, said chassis including a loudspeaker, and an antenna positioned in the lamp shade, characterized in that the antenna comprises a loop vertically positioned and rotatable within and independently of the lamp shade.

2. A radio apparatus comprising, in combination, a table lamp having a hollow pedestal, a cover, and a shade, and a radio receiving set having a chassis positioned in the pedestal of the lamp, said chassis including a loudspeaker, and an antenna positioned in the lamp shade, characterized in that the antenna is formed on a loop of transparent material vertically positioned and rotatable in and independent of the lamp shade.

3. A radio apparatus comprising, in combination, a table lamp having a hollow pedestal, a cover, and a shade, and a radio receiving set having a chassis positioned in the pedestal of the lamp, said chassis including a loudspeaker, and an antenna positioned in the lamp shade, characterized in that the antenna comprises a transparent plastic frame rotatable independently of the lamp and shade.

4. A radio apparatus comprising, in combination, a table lamp having a hollow pedestal, a cover, and a shade, and a radio receiving set having a chassis positioned in the pedestal of the lamp, said chassis including a loudspeaker, and an antenna positioned in the lamp shade, characterized by means on the chassis for projecting numerals corresponding with calibrations of the tuning condenser on the face of the pedestal.

5. A radio apparatus comprising, in combination, a table lamp having a base, a hollow pedestal, a cover, light bulbs, and a shade, and a radio receiving set having a chassis positioned in the pedestal of the lamp, said chassis including a loudspeaker, an antenna positioned in the lamp shade and operating knobs, characterized in that the radio chassis, antenna, and lamp parts are connected to the cover and removable therewith.

6. In a radio receiving set of the character described, in combination, a radio receiving apparatus and a lamp structure, said lamp structure including a shade, a hollow pedestal, and a cover arranged on said pedestal, said radio apparatus comprising a chassis having component receiver parts and a loudspeaker mounted thereon, said chassis being carried by said cover, a loop antenna unit vertically supported upon means connected to said cover, said antenna unit being independently rotatable with respect to said lamp shade.

7. In a radio receiving set of the character described, in combination, a radio receiving apparatus and a lamp structure, said lamp structure including a shade, a hollow pedestal, and a cover arranged on said pedestal, said radio apparatus comprising a chassis having component receiver parts and a loudspeaker mounted thereon, said chassis being mounted upon said cover and depending therefrom into said pedestal, a loop antenna unit vertically supported upon said cover and rotatable within the lamp shade and independently thereof, said cover, chassis, and lamp structure being removable from said pedestal as a complete unit.

15. 8. A radio apparatus comprising, in combination, a table lamp having a shade, a hollow pedestal, a cover connected to said pedestal, and a radio receiving set comprising a chassis positioned in the pedestal of the lamp and having component receiver parts and a loudspeaker mounted thereon, said chassis being supported by a stem extending through said cover, and a loop antenna positioned in the lamp shade and also carried upon said stem, said antenna being rotatable within the lamp shade and independently thereof.

9. In a combination radio receiving set and lamp in which an antenna loop of the radio is vertically positioned and independently rotatable in a shade of the lamp, a sleeve positioned around a supporting stem of the lamp and interposed between a pedestal thereof and said shade, said stem of the lamp providing support and control means for said antenna loop, said control means permitting directional tuning of the antenna by the rotation of the antenna loop about the supporting stem.

10. In a combination radio receiving set and lamp, a base, a nipple secured to said base, a radio receiving set connected to said nipple, a hollow pedestal arranged on the base and accommodating said radio receiving set, a cover member mounted on the pedestal, a tubular member projecting upwardly from said cover member, a vertically positioned loop antenna rotatably mounted on said tubular member, a lamp shade connected to the tubular member and normally screening said loop antenna from view, and lamp bulbs operatively supported on the tubular member.

11. In a combination radio receiving set and lamp, a hollow pedestal, a radio receiving set and a loudspeaker arranged within said hollow pedestal, a cover member mounted on the pedestal, a plurality of radio control elements protruding upwardly from the radio set and disposed on said cover member in spaced relation, a tubular element protruding upwardly from the cover member and rotatably supporting a loop antenna, lighting instrumentalities operatively arranged on the element, and a lamp shade supported on the said element and screening said loop antenna and lighting instrumentalities from view.

12. In a combination radio receiving set and lamp, in combination, a hollow pedestal, a radio receiving set arranged within the pedestal, a cover member mounted on the pedestal, and operatively accommodating a pair of control means connected to the radio, a vertically positioned tubular member projecting upwardly from the cover member, a loop antenna rotatably mounted on the tubular member, lighting instrumentalities connected to the tubular member, a lamp shade secured to the tubular member and normally screening the loop antenna and the light instrumentalities from view, and means

connected to the radio receiving set and effective for projecting illuminated dial numbers on the pedestal.
